(57) **CLAIM**

The ornamental design for an inlet cover plate, as shown and described.

DESCRIPTION

FIG. 1 is a top perspective view of an inlet cover plate showing my new design;

FIG. 2 is a bottom perspective view thereof;

FIG. 3 is a top plan view thereof;

FIG. 4 is a side view, the opposite side being a mirror image thereof;

FIG. 5 is an end view thereof;

FIG. 6 is an opposite end view thereof;

FIG. 7 is a cross sectional view thereof, taken along line 7—7 of FIG. 3; and,

FIG. 8 is a bottom plan view thereof.
